UNITED STATES PATENT OFFICE.

WILLIAM F. WEGNER, OF NEW YORK, N. Y., ASSIGNOR OF ONE-HALF TO MORLAND A. BROWER, OF NEW YORK, N. Y.

STEAM BOILER.

1,408,052.

Specification of Letters Patent. Patented Feb. 28, 1922.

Application filed August 23, 1921. Serial No. 494,651.

To all whom it may concern:

Be it known that I, WILLIAM F. WEGNER, a citizen of the United States, and resident of the borough of Manhattan, in the city and 5 State of New York, have invented a new and useful Improvement in Steam Boilers, of which the following is a specification.

The object of my invention is to provide a steam boiler having novel means provided 10 whereby gas supplied from different sources can be mixed for producing a high degree of heat in the fire box.

My invention more particularly includes a gas generating means located within the fire 15 box, the gas from which may be mixed with the ordinary city illuminating gas in the fire box to obtain a high degree of heat.

A practical embodiment of my invention is represented in the accompanying drawings, in which

Fig. 1 represents my improved steam boiler in longitudinal vertical central section.

Fig. 2 represents a transverse section taken 25 in the plane of the line II—II of Fig. 1.

The boiler in connection with which I have illustrated my invention is of the well known horizontal water tube type. The side walls of the boiler are denoted by 1 and 2, 30 the front wall by 3 and the back wall by 4. The fire box is denoted by 5 and in lieu of the usual grate at the bottom of the fire box I have shown a bottom wall 6 of firebrick or other fire resisting material. Along the 35 rising sides 7 and 8 of this fire box bottom 6, I locate two series of nozzles 9 and 10 of burners which are connected to horizontally disposed longitudinal pipes 11 and 12 leading to pressure feeding means, such as rotary 40 blowers 13 (one only of which is shown herein). A gas supply pipe 14 leads from a source of gas supply, such for instance as the usual city illuminating gas supply, to the pressure feeding means.

45 These series of nozzles 9 and 10 are preferably located in the strips 15 and 16 of extra hard fire resisting material inset into the uprising sides 7 and 8 of the fire box bottom 6. These nozzles 9 and 10 are preferably directed slightly downwardly toward the said bottom 6 to ensure a complete admixture of the gas from this source with the gas from the additional source, the means

for supplying which will be immediately described.

I locate an additional source of gas generating means within the fire box which means is herein shown as comprising a series of horizontally arranged gas generating tubes 17 which are supported by and extend 55 through the front wall 3 of the boiler into the fire box 5, above the nozzles 9 and 10 of the illuminating gas burners. These gas generating tubes 17 are filled with difficultly fusible material 18 in a broken-up state, the 60 difficultly fusible material being preferably of a gas generating character such for instance as manganese dioxide which at a high temperature yields oxygen according to the equation, $3\text{MnO}_2 = \text{Mn}_3\text{O}_4 + \text{O}_2$. 65

70 Gas pipes 19 lead from the gas generating tubes 17 to two series of burners, the nozzles 20, 21 of which extend upwardly through the bottom 6 of the fire box. These nozzles are arranged in position to cause a complete 75 and thorough admixture of the gas issuing therefrom with the gas issuing from the nozzles 9 and 10 of the main source of illuminating gas supply.

75 Steam pipes 22 lead from a source of steam supply into the gas generating tubes 17. Liquid hydrocarbon supply pipes 23 communicate with the steam supply pipes 22 so as to be mixed with the steam when so desired and forced into the gas generating 85 tubes 17.

Manually controlled valves 24 are provided for controlling the admission of the liquid hydrocarbon into the steam supply pipes 22. 90

Where the gas generating tubes 17 are filled with a gas generating material, such for instance as an oxygen gas generating material, as manganese dioxide, it may be only necessary to force the steam therethrough 95 for producing oxygen gas which can be used to be mixed with the gas from the source of illuminating gas supply in the fire box to obtain a high degree of heat.

Where the gas generating tubes are filled 100 with infusible material which is not of itself gas generating, the liquid hydrocarbon may be forced through the said tubes and there broken up into the form of a suitable gas for use in connection with the said illuminating gas in the fire box. 105

- From the above description it will be seen that I have provided effective means for producing a gas to be used in combination with the gas fed from the main source of illuminating gas supply in the fire box whereby the character of the illuminating gas may be changed to intensify the heat of its products of combustion to a point where it may be successfully used in a steam boiler.
- 10 While I have illustrated my invention in connection with a well known type of horizontal water tube boiler, it is to be understood that I do not wish to limit myself to that particular type of boiler but contemplate 15 the application of my invention to boilers of any type where this invention would be applicable. It is also evident that various changes may be resorted to in the construction, form and arrangement of the several 20 parts of my invention without departing from the spirit and scope of the same, hence I do not wish to limit myself to the particular embodiment herein shown and described, but
- 25 What I claim is:—
1. In a steam boiler, a fire box, a source of illuminating gas supply, a gas generating device located in the fire box and containing difficultly fusible material, means for feeding steam and liquid hydrocarbon to said gas generating device, and means for leading gas from both said source of gas supply and said gas generating device into the fire box for combination therein of their products of combustion.
  2. In a steam boiler, a fire box, a source of illuminating gas supply, a gas generating device comprising a series of horizontally arranged tubes located in the fire box and containing difficultly fusible material, means for feeding steam and liquid hydrocarbon to said gas generating device, and means for leading gas from both said source of gas supply and said gas generating device into the fire box for combination therein of their products of combustion.
  3. In a steam boiler, a fire box, a source of illuminating gas supply, a gas generating device located in the fire box and containing difficultly fusible gas generating material, means for feeding steam to said gas generating device, and means for leading gas from both said source of gas supply and said gas generating device into the fire box for combination therein of their products of combustion.
  4. In a steam boiler, a fire box, a source of illuminating gas supply, a gas generating device comprising a series of horizontally arranged tubes located in the fire box and containing difficultly fusible gas generating ma-

terial, means for feeding steam to said gas generating device, and means for leading gas from both said source of gas supply and said gas generating device into the fire box for combination therein of their products of combustion.

5. In a steam boiler, a fire box, a source of illuminating gas supply, a gas generating device located in the fire box and containing difficultly fusible gas generating material, means for feeding steam and liquid hydrocarbon to said gas generating device, and means for leading gas from both said source of gas supply and said gas generating device into the fire box for combination therein of their products of combustion.

6. In a steam boiler, a fire box, a source of illuminating gas supply, a gas generating device comprising a series of horizontally arranged tubes located in the fire box and containing difficultly fusible gas generating material, means for feeding steam and liquid hydrocarbon to said gas generating device, and means for leading gas from both said source of gas supply and said gas generating device into the fire box for combination therein of their products of combustion.

7. In a steam boiler, a fire box, one or more series of burners in the bottom of the fire box, a gas generating device located in the fire box and connected to said burners, other burners located in the bottom of the fire box, and a source of illuminating gas supply connected to said last named burners.

8. In a steam boiler, a fire box, a series of burners in the bottom of the fire box connected to a source of illuminating gas supply, two other series of burners located in the bottom of the fire box adjacent to the two first named series of burners, and a gas generating device located in the fire box and connected to the second named two series of burners whereby the gas from the two series of gas supply will be combined within the fire box.

9. In a steam boiler, a fire box, a series of burners in the bottom of the fire box connected to a source of illuminating gas supply, two other series of burners located in the bottom of the fire box adjacent to the two first named series of burners, and a gas generating device comprising a series of horizontally arranged tubes located in the fire box and connected to the second named two series of burners whereby the gas from the two sources of gas supply will be combined within the fire box.

In testimony, that I claim the foregoing as my invention, I have signed my name this 20th day of August 1921.

WILLIAM F. WEGNER.
